UNITED STATES PATENT OFFICE

148,453

DESIGN FOR A MEAT HOLDER AND CARVER'S AID

Philip Betten and Maxwell Lehrhaupt,
Brooklyn, N. Y.

Application February 21, 1946, Serial No. 126,782

Term of patent 14 years

(Cl. D11—1)

To all whom it may concern:

Be it known that we, Philip Betten and Maxwell Lehrhaupt, both being citizens of the United States, residing at Brooklyn, in the county of Kings, city and State of New York, and whose post office address is 551 Fifth Avenue, New York, N. Y., have invented a new, original, and ornamental Design for a Meat Holder and Carver's Aid, of which the following is a specification, reference being made to the accompanying drawing, forming a part thereof.

Fig. 1 is a front view of a meat holder and carver's aid, showing our new design; and

Fig. 2 is a top view thereof.

We claim:

The ornamental design for a meat holder and carver's aid, substantially as shown.

PHILIP BETTEN.
MAXWELL LEHRHAUPT.
